W. S. GRIFFITH,
MAGNETIC CHUCK.
APPLICATION FILED JUNE 24, 1913.

1,232,532.

Patented July 10, 1917.

UNITED STATES PATENT OFFICE.

WINFRED S. GRIFFITH, OF WORCESTER, MASSACHUSETTS, ASSIGNOR TO HEALD MACHINE COMPANY, OF WORCESTER, MASSACHUSETTS, A CORPORATION OF MASSACHUSETTS.

MAGNETIC CHUCK.

1,232,532.

Specification of Letters Patent. Patented July 10, 1917.

Application filed June 24, 1913. Serial No. 775,455.

To all whom it may concern:

Be it known that I, WINFRED S. GRIFFITH, a citizen of the United States, residing at Worcester, in the county of Worcester, State 5 of Massachusetts, have invented a certain new and useful Improvement in Magnetic Chucks, of which the following is a specification, reference being had therein to the accompanying drawings.

10 This invention relates to rotary chucks but more particularly to those of the magnetic type and has for its object to provide a structure which shall be more durable and more efficient than any device of a similar 15 nature heretofore known.

In the forms of chucks now in common use, electro-magnets having cast iron faces are seated in the body of the chuck and these faces are generally in the form of a sector 20 of a circle. These faces soon wear off and their holding action is comparatively weak.

25 In order to obviate these difficulties, a chuck has been devised in which the operating faces of the magnetic members are of magnet steel and of a peculiar form which will be fully described hereinafter and which produces great holding power.

30 The many other features and advantages of the invention will be fully described hereinafter and included in the claim.

One embodiment of the invention is shown in the drawings in which:—

Figure 1 is a plan view of the invention complete, and

35 Fig. 2 a section on the line 2—2 of Fig. 1.

Referring to the drawings, the device is shown to comprise a body portion 10 in which are set a plurality of electro-magnets 11 having their operating faces 12 elongated. Each of these magnets comprises a plate from which projects at substantially a right angle to the operating face 12 a flange 13 about which electric wiring 13^a is wound. These magnetic members 11 rest in slots 14 40 in the body portion 10 and the face plates are preferably of slightly smaller size than the slot. In the interval between the rim of the face plate and the opposing wall of the slot is preferably set in babbitt, type metal 45 or other suitable substantially nonconducting material.

To the base of the body 10 is secured a retaining plate 15 by means of screws 16. Similar screws 17 secure the base of each of 50 the magnet members 11 to this plate 15.

No broad claim is made by the applicant to a chuck composed of a body having magnet members mounted therein as this is known to be old, but the form of the magnet members and the method of mounting them in this body is believed to be new and produces a very advantageous result.

By making the operating plates long and narrow, an extremely large holding surface is obtained and a much more powerful hold 65 may be obtained by the chuck than where these plates are otherwise formed. These plates are preferably set parallel to one another in the body and may be integral with the flanges 13 or secured thereto in any desired way.

At the rear face of the plate 15 is secured a sleeve 18 of wood or other substantially non-conducting material and upon this sleeve are set two electrical contact rings 19 and 20 of 75 copper or other suitable conducting material. The wire coils enveloping the magnets are preferably joined together in series and one pole is secured to the ring 19 and the other pole to the ring 20, as is indicated by dotted 80 lines in Fig. 2 of the drawings. A face plate seat 21 is provided.

With the cast iron chuck, the magnetic members were cast as a part of the plate corresponding to the present plate 15. To so 85 form the chuck with steel faces on the magnet members would be an exceedingly difficult and expensive operation. By having the magnet members detached from the plate and secured thereto, the plate may be made 90 of any suitable material and the steel members may be produced at small expense. Also any one may be replaced without replacing the whole.

This chuck is constructed to be attached 95 to the live spindle of a lathe in the manner usual to rotary chucks.

The applicant is aware that a large number of changes in the construction and arrangement of parts might be made by any 100 one skilled in the art without departing from the scope of his invention as defined by the appended claim and he does not care to be limited to the particular embodiment herein shown and described.

105 What I claim as my invention and desire to secure by Letters Patent is:—

In a device of the class described, a single piece cast body provided with a plurality of 110 slots in the front face thereof, a single polar

extension core in each of said slots insertible from the rear, an energizing coil for each of said cores, a retaining plate secured to the rear face of such body, and means for fastening the rear end of each of said cores to the front face of said plate.

In testimony whereof I affix my signature in the presence of two witnesses.

WINFRED S. GRIFFITH.
